UNITED STATES PATENT OFFICE

HARVEY CARLSON, OF CHEBOYGAN, MICHIGAN

LAMP

Application filed June 17, 1929. Serial No. 371,488.

This invention aims to provide a lamp including a revolving lantern. One object of the invention is to provide novel means for mounting the lantern for rotation, and to provide means for rotating the lantern. A further object of the invention is to improve the construction of the lantern. Another object of the invention is to supply novel means whereby the lamps of the lantern may be kept alight whilst the lantern is being rotated.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawings:

Figure 1 shows in side elevation, a device constructed in accordance with the invention;

Figure 2 is a vertical longitudinal section on an enlarged scale, parts being broken away;

Figure 3 is a top plan of a portion of the lantern;

Figure 4 is a cross section on the line 4-4 of Figure 2;

Figure 5 is a cross section on the line 5-5 of Figure 2.

The device forming the subject matter of this application comprises a support including a base 1 having a recess 2 in its bottom. A hollow pedestal 3 is mounted on the base 1. Near to its upper end, the pedestal 3 has a shoulder 4. A hollow cup-shaped head 5 is mounted on the upper end of the pedestal 3 and forms part of the pedestal. The device includes a lantern journaled for rotation on the pedestal, the lantern being designated as a whole by the numeral 6.

The lantern 6 includes a bottom 7 mounted

to turn on the pedestal 3 about the shoulder 4. A ball bearing 8 is interposed between the shoulder 4 and the bottom 7 of the lantern. The bottom 7 of the lantern 6 has an annular chamber 9. The lantern comprises a top 10 supported from the bottom 7 by hollow posts 11 which are secured in both the top 10 and the bottom 7. Upwardly-extended, diverging arms 12 are secured to the edge of the bottom 7. Anchor hooks 14 are mounted on the top 10. The lower end of stay chains 15 are secured to the arms 12, at points near to the outer ends of the arms, each chain being mounted at its upper end on one of the anchor hooks 14. In their inner surfaces, the arms 12 have longitudinal grooves 16. Cover strips 17 are mounted on the inner edges of the arms 12 and convert the grooves 16 into passages in the arms. Sockets 18 are mounted on the outer ends of the arms 12. Electric lamps 19 are carried by the sockets 18. The top 10 has an upstanding, annular rim 20, about which fits a cap 21 supported on the top 10. The top 10 has a shoulder 22 located within the rim 20. On the shoulder 22 is secured a cross bar 23, preferably made of metal. In the cross bar 23 is received the squared end 24 of a vertical shaft 25 extended downwardly through the pedestal 3, the shaft being journaled at its lower end in a bearing 26 mounted on the base 1 within the recess.

A beveled gear 27 is secured to the lower end of the shaft 25. The beveled gear 27 meshes with a beveled pinion 28 on a horizontal shaft 29 journaled for rotation in the base 1 and in bearings 30 carried by the base and located in the recess 2. Any suitable means, however, may be employed for rotating the shaft 25. Figure 4 shows that in the upper surface of the head 5 there are seats or notches 31, which can be seen, also, in Figure 2. The seats 31 are adapted to receive pins 32 which project from a lower insulating block 33 supported within the head 5. A bearing 34 of tubular form is journaled in the block 33 and is secured at 35 to the shaft 25, the bearing 34 receiving the shaft 25. A ball bearing 36 is disposed about the insulating block 33 and is interposed between the head 5 and the top 10 of the lan-

tern, to aid in supporting the lantern anti-frictionally for rotation on the pedestal. The lower insulating block 33 has an up-standing rim 37, within which extends an upper insulating block 38. The bearing 34 extends up into the upper insulating block 38 and aids in keeping it centered. A bridge bar 39 is secured to the upper insulating block 38. The squared end 24 of the shaft 25 extends upwardly through the bridge bar 39, and, therefore, when the shaft 25 is rotated, rotation will be imparted to the upper insulating block at the same time that rotation is imparted to the top 10 of the lantern.

15 An outer conducting ring 40 is mounted on the lower insulating block 33. An inner conducting ring 41 is mounted on the lower insulating block 33. An outer conducting ring 42 is mounted on the upper insulating block 38. An inner conducting ring 43 is mounted on the upper insulating block 38. The inner conducting ring 43 bears slidably on the inner conducting ring 41 and the outer conducting ring 42 bears slidably on the outer conducting ring 40. A compression spring 44 surrounds the squared end 24 of the shaft 25. The upper end of the spring 44 engages an abutment 45 on the part 24 of the shaft 25. The lower end of the spring 44 presses downwardly on the bridge bar 39. The purpose of the spring 44 is to press down the upper insulating block 38, so that the ring 42 has a good electrical contact with the ring 40, the ring 43 having a corresponding contact with the ring 41. There are binding posts 46 on the lower insulating block 33, the posts extending downwardly into the hollow head 5. The binding posts 46 are in electrical engagement with the conducting rings 40 and 41. Conductors 47 are connected to the binding posts 46. The conductors 47 extend downwardly through the hollow pedestal 3. Binding posts 49 are mounted on the upper insulating block 38 and are in electrical connection with the rings 42 and 43. Conductors 50 connect the binding posts 49 with the lamps 19.

In practical operation, when the shaft 29 is rotated, the beveled pinion 28 and the beveled gear 27 will rotate the shaft 25. The shaft 25 will rotate the lantern 6, because the squared end 24 of the shaft 25 is received in the cross bar 23 that is attached to the top 10 of the lantern. The squared end 24 of the shaft 25 also rotates the upper insulating block 38, because the end 24 of the shaft is received in the bridge bar 39. When the lantern 6 is rotated the lamps 19 will be carried around in an orbit, with a pleasing effect which can be taken advantage of for advertising, and for many other purposes, in the home, as well as in public. It will be obvious that since the rings 40—42 and 41—43 are in 65 slidable contact with each other, the lantern

6 can be rotated, as aforesaid, without breaking the continuity of the lamp circuit.

Having thus described the invention, what is claimed is:

1. In a device of the class described, a pedestal, a lantern journaled on the pedestal, an electric lamp on the lantern, a circuit for the lamp located partly on the lantern and partly on the pedestal, mechanism interposed in said circuit for maintaining the continuity thereof when the lantern is rotated on the pedestal, said mechanism comprising an insulating block on the lantern, an insulating block on the pedestal, and contact members on the blocks; a shaft extended longitudinally of the pedestal, means for journaling the shaft in the insulating block of the pedestal, means for connecting the shaft to the insulating block of the lantern to secure a rotation of the said block, and means for connecting the shaft to the upper portion of the lantern to secure a rotation of the lantern.

2. In a device of the class described, a lantern comprising a base, a top, hollow posts connecting the base and the top, outwardly extended arms on the base, electric lamps on the arms, a pedestal whereon the lantern is journaled, a circuit for the lamps, said circuit being extended upwardly through the pedestal, downwardly through the top, the posts and the base, and upwardly along the arms to the lamps, and mechanism interposed in said circuit for maintaining the continuity thereof when the lantern is rotated on the pedestal.

3. In a device of the class described, a lantern comprising a base, a hollow top, a cap resting on the top and constituting a closure therefor, hollow posts connecting the base and the top, extended arms on the base, electric lamps on the arms, stays extended between the top and the arms, a pedestal whereon the lantern is journaled, a circuit for the lamps, said circuit being extended upwardly through the pedestal, downwardly through the top, beneath the cap, downwardly through the posts and the base, and upwardly along the arms to the lamps, and mechanism interposed in said circuit for maintaining the continuity thereof when the lantern is rotated on the pedestal.

4. In a device of the class described, a pedestal having a head at its upper end and provided with a shoulder located below the head, a lantern including a base, a top, posts connecting the base with the top, and arms extended upwardly from the base, lamps on the arms, the base being supported on the shoulder, and a circuit including the lamps, the circuit being located partly on the lantern and partly on the pedestal, and mechanism interposed in said circuit for maintaining the continuity thereof when the lantern is rotated on the pedestal, a portion of said

mechanism being carried by the head of the pedestal, and a cooperating part of the mechanism being carried by the top part of the lantern.

5 In testimony that I claim the foregoing as my own, I have hereto affixed my signature.

HARVEY CARLSON.
